UNITED STATES PATENT OFFICE.

JOHN MEHL, JR., OF JERSEY CITY, NEW JERSEY.

DESIGN FOR A BELT-BODY.

SPECIFICATION forming part of Design No. 32,600, dated April 24, 1900.

Application filed March 27, 1900. Serial No. 10,403. Term of patent 3½ years.

To all whom it may concern:

Be it known that I, JOHN MEHL, Jr., a citizen of the United States, and a resident of Jersey City, in the county of Hudson and State 5 of New Jersey, have invented and produced a new and original Design for a Belt-Body, of which the following is a specification.

The essential feature of my design consists in a belt-body having its outer surface embellished with ribs developed into loops or bights 10 at the back of the body of the belt.

In the accompanying drawings, Figure 1 is an outside view of the belt-body, and Fig. 2 is a transverse section along the line 2 2 of 15 Fig. 1.

The belt-body as a whole is denoted by A. The ribs B B' have their loops or bights b b'

located in proximity to each other at the middle of the back of the belt, the branches extending thence in opposite directions toward 20 the opposite ends of the belt-body. Within the bights b b' of the loops B B' are located the loops c c' of intermediate ribs C C'.

What I claim is—

The design for a belt-body, substantially 25 as herein shown and described.

In testimony that I claim the foregoing as my invention I have signed my name, in presence of two witnesses, this 23d day of March, 1900.

JOHN MEHL, JR.
